James H. Fiske

— INVENTOR.

UNITED STATES PATENT OFFICE.

JAMES H. FOOTE, OF CINCINNATI, OHIO.

SASH-PULLEY.

1,386,774.

Specification of Letters Patent. Patented Aug. 9, 1921.

Application filed February 21, 1921. Serial No. 446,836.

To all whom it may concern:

Be it known that I, JAMES H. Foote, a citizen of the United States, residing at the city of Cincinnati, in the county of Hamilton and State of Ohio, have invented new and useful Improvements in Sash-Pulleys, of which the following is a specification.

My invention relates to sash pulleys and the like, and more particularly to their housings and the form and manner of arrangement of the structural members composing same for securing such pulleys in their mounting frames; the object of the present invention being, to provide an effective and inexpensive housing that will avoid the use of screws or special devices for securing the sash pulley in its mounting frame; another object being to provide a sash pulley housing that will not be curtailed in efficiency by a considerable range in relative thickness of the material used for making the frame member in which the opening for the sash pulley to seat in is formed; a further object being to provide a sash pulley that may be installed in a window frame after it is completed as easily and expeditiously as this can be done while the frame is in course of construction.

I attain these and other objects by mechanism such as illustrated in the accompanying drawing, in which:—

Figure 1 is a view in side elevation of a pulley embodying my invention, seated and secured in the opening formed for it to fit in a window frame member, which latter is shown in fragmentary vertical section; Fig. 2 is a view similar to Fig. 1 but showing the pulley entering the frame opening with the housing members relatively positioned to facilitate inserting the pulley and bringing it to seated position in said opening; Fig. 3 is a view in rear elevation of the supporting member shown in Fig. 1, detached from the other parts of the device; Fig. 4 is a view in front elevation of the sheave bearing hood member of the housing shown in Fig. 1, detached from the supporting member and in the position the sheave and its journal would occupy indicated in

dotted outline; Fig. 5 is a view similar to Fig. 1, but showing a pulley embodying my invention in a modified form.

Although I have shown my improved housing as formed of sheet metal, it will be understood that in accordance with well known practice, the housing members, or either of them, may be formed by other means than sheet metal, and while for convenience in illustration I have utilized a fragment of a wooden or "kalamein" window frame, it will be understood that my device is intended for use in all frames in which pulleys are a requirement, irrespective of their character, the use to which they may be put or the nature of the material used in their construction.

Referring to Figs. 1 to 4 inclusive, of the drawing, A represents the supporting member of a sash pulley housing embodying my invention, comprising a front plate a which may be extended to engage a front face of a window frame member W, and is provided with a central aperture I for the passage of a sheave C, and a pair of side walls a' which extend rearwardly from plate a and are turned in at their ends to meet, or are connected by a suitable member, to form an upper and lower cross wall a^2 to sustain the thrust of member A against the ends of an opening O which is formed in the window frame member W for member A to seat in, and each of cross walls a^2 may be provided with an extension a^3 to engage the front face of member W, adjacent the ends of opening O, to limit the movement of member A in one direction into said opening O.

In each side wall a' a vertically inclined slot d, which may be cut back somewhat at its upper end to facilitate the operation of installing the device in the window frame opening O, is formed to provide a confining runway for the bottom e of a rearwardly facing hook or channel b^4 which is located at the front of an extension b' of each side wall b of a second housing member B to which the sheave C is journaled.

And in a plane approximating that of

the lower end of slot d in each side wall a' , a tongue of the metal of side wall a' is cut loose and bent inwardly to form a flange k to engage a lower edge b^3 of each side wall 5 extension b' of housing member B, to limit the downward movement of member B and help take the thrust of member B upon its coming to supported position in member A.

Housing member B comprises a pair of 10 substantially parallel side walls b having upper and lower forwardly facing edges b^5 adapted to engage the rear face of the window frame member W and to embed therein more or less as may be required by the thickness 15 of the particular frame member engaged, and which side walls b are preferably connected and spaced at their upper ends by a cross member b^6 to serve as a hood for the sheave, and are provided with median front extensions b' from each of which, adjacent its upper forward end, a bit of the metal is loosened and forced out slightly to form a catch or detent k' , adapted to enter slot d of member A and engage its 20 downwardly directed upper edge d^2 and releasably lock member B against upward movement when it comes to supported position in member A, and from each of which extensions b' a tongue of the metal is loosened 25 and bent out and over to form, with the side of said extension for its inner wall, a rearwardly facing hook or channel b^4 having a bottom wall e and an outer wall e' .

Hooks b^4 are adapted to fit over portions 30 of side walls a' of member A bordering upon slots d , and to slidably engage with their bottom walls e the forwardly facing edges d' of these portions.

Edges d' also form the rear boundary 35 of edges of slots d , within which the bottom walls e of hooks b^4 are movably confined, and against the lower edge of which slots, the lower ends of bottom walls e are adapted to seat and help sustain the thrust of member B when it comes to supported position in member A.

In assembling the parts for a complete pulley, sheave C may be first journaled to member B, and member B may then be 40 movably connected to member A by passing hooks b^4 of side wall extensions b' of member B, in between side walls a' of member A until the rearwardly facing edges of the outer walls e' of these hooks pass the forwardly facing edges d' of the side walls a' portions of member A, entering these portions into hooks b^4 by pressing in edges d' slightly out of alignment with the opposite edges of slots d , and withdrawing member 45 B from member A until edges d' come to a bearing upon the bottom walls e of hooks b^4 , whereupon, edges d' may be returned into alignment with the opposite edge of slots d , movably confining bottoms e of the hooks, 50

in slots d of member A and in sliding engagement with edges d' of the portions of walls a' engaged by the hooks b^4 thus providing easily manipulated interlocking means for establishing and maintaining a movable connection between the housing members 70 and enabling them to undergo change in relative position.

To install the pulley in the window frame, the housing members are first moved into substantially the relative position shown in Fig. 2, the device is then inserted into the frame opening, upper end first, and the supporting member A of the housing brought to seated position, member B, to which the sheave is journaled, is then pushed back until its lower front edges b^5 clear the lower inner edge of the frame opening O, and allowed to drop into supported position in supporting member A, during which movement its upper and lower engaging faces b^5 move forward into clamping engagement with the rear face of the frame member 80 clamping supporting member A to the front face of the frame member and securing the pulley in seated position in frame opening 90 O.

When it comes to this position the housing members are releasably locked against relative movement by catches k' which then are moved out into slots d and engage the downwardly facing upper end edge d^2 of these slots by reason of the return to normal position of extensions b' of member B and walls a' of member A, which are sprung apart slightly by catches k' as member B 100 passes downwardly into supported position in member A.

When the thickness of frame member W is such that the sheave bearing member B will not drop into supported and locked position by its own weight, it will be carried down into this position by the sash cord in its passage over the sheave with the weight attached at one of its ends and the sash at the other, or it may be readily forced down 110 by the use of an ordinary tool, as for instance a screw driver, which may be employed as a lever utilizing plate a, at one end of aperture I, as a fulcrum.

By inserting the point of a screw driver blade or other suitable tool between wall extensions b' of member B and walls a' of member A, catches k' may be easily released from locked engagement and the pulley removed by a reversal of the operation described for installing it.

In Fig. 5, a modified form of my invention is illustrated, in which the flanges formed in the side walls of the supporting member, to take the thrust of the sheave bearing member of the housing, are eliminated, and in which the sheave bearing member, by carrying forward its side walls,

somewhat, at their lower ends, is provided with a base b^7 to seat in the frame opening O and sustain the thrust of this member against the end of said opening.

5 Aside from these differences in form and purpose of its housing members, the device in this modified form, in the arrangement of its parts and manner of use as well as in the operation required for installing it, is 10 substantially similar to the form of pulley already described.

Other modifications of the invention herein disclosed may be made and need not be illustrated, as modifications within the 15 spirit and scope of the invention as pointed out in the claims, will be obvious to those skilled in the art.

Having thus described my invention, what I claim as new is;—

20 1. A sash pulley comprising a sheave, a housing member adapted to fit into an opening in a window frame member, and provided with means to engage the front face of the frame member to limit the movement 25 of said housing member in one direction into said opening, and with means to sustain the thrust of said housing member against the end of said opening, and a hood member to which said sheave is journaled, carried by 30 and movable relative to said housing member, to releasably engage a rear face of the frame member and lock said housing member to the frame member irrespective of a considerable range in thickness of said frame 35 member.

2. A sash pulley comprising a sheave, a housing member adapted to fit into an opening in a window frame member, and provided with means to engage the front face of 40 the frame member to limit the movement of said housing member in one direction into said opening, and with means to sustain the thrust of said housing member against the end of said opening, a hood member to 45 which the sheave is journaled, carried by and movable relative to said housing member, to releasably engage the rear face of the frame member and lock said housing member to the frame member irrespective of a 50 considerable range in thickness of said frame member, and means to releasably maintain said hood member in the relative position selected for locking said housing member to the frame member, and releasably secure the pulley in the opening in said frame member.

3. A sash pulley adapted to seat in an opening in a window frame member, comprising a sheave bearing housing having a supporting element adapted to fit into the opening in the frame member and provided with means to engage the front face of the frame member to limit the movement of said element in one direction into said opening, and with means to sustain the thrust of said ele-

ment against the end of said opening, a hood 65 element, to which the sheave is journaled, adapted to fit into the opening in the frame member and provided with means to sustain the thrust of said hood element against the end of said opening, connected to and held in 70 relatively movable engagement by said supporting element and adapted to releasably engage the rear face of the frame member and lock the supporting element to the frame member irrespective of a considerable 75 range in thickness of said frame member, and means to maintain said supporting and hood elements in locked relation with said frame member.

4. A sash pulley adapted to seat in an 80 opening in a window frame member comprising, a sheave, a housing for the sheave, having a front element, adapted to fit into the opening in said frame member, provided with a centrally apertured front plate, side 85 walls, connected at their ends to form an upper and a lower wall to sustain the thrust of said front element against the ends of said opening, and provided with means to engage a front face of the frame member and limit 90 the movement of said element in one direction into said opening, a rear element adapted to serve as a hood for the sheave, having suitably connected side walls, between and to which said sheave is journaled, provided 95 with means to engage a rear face of the frame member, means to connect and maintain the rear element in relatively movable engagement with the front element, means to take and to sustain the thrust of the rear ele- 100 ment against the front element and means to limit the movement of said rear element relative to said front element, whereby the housing elements may be relatively positioned to facilitate seating the pulley in the 105 opening in the window frame member and securing it in said opening by said housing elements.

5. A sash pulley adapted to seat in an 110 opening in a window frame member comprising, a sheave, a housing for the sheave, having a front element, adapted to fit into the opening in said frame member, provided with a centrally apertured front plate, side 115 walls, connected at their ends to form an upper and a lower wall to sustain the thrust of said front element against the ends of said opening, and with means to engage a front face of the frame member and limit the movement of said front element in one 120 direction into said opening, a rear element, adapted to serve as a hood for the sheave, having side walls, between and to which said sheave is journaled, provided with means to engage a rear face of the frame member, 125 means on the side walls of said housing elements to connect and maintain the rear element in relatively movable engagement with

the front element, means on said side walls to take and to sustain the thrust of the rear element against the front element and means on said walls to limit the movement of the rear element relative to the front element, whereby the said housing elements may be relatively positioned to facilitate seating the pulley in the opening in the window frame

member and moved into locking engagement with the front and rear faces of said frame member to lock the pulley in said opening.

In testimony whereof I have hereunto subscribed my name this 14th day of February, 1921.

JAMES H. FOOTE.
